REVERSIBLE FRONT CUFF LINK

William H. Meeker, Rochester, N. Y., assignor to
Hickok Manufacturing Company, Inc., Rochester, N. Y., a corporation of New York

Application August 22, 1949, Serial No. 111,640

9 Claims. (Cl. 24—97)

1

This invention relates to a reversible front member for cuff links.

One object of the invention is to provide a cuff link having a reversible front member carrying contrasting colors or other differing design characteristics on its inner and outer faces to be presented to view, interchangeably, as may be desired by the wearer.

Another object of the invention is to provide a cuff link including a reversible front member composed of an ornamental metal or other element carrying against one face thereof a stone or other element of substantially the same shape as the shape of the metal element and having different color or design from that of the ornamental metal element.

Another object of the invention resides in the provision of a cuff link including a reversible front member carrying contrasting colors or designs on opposite faces thereof and in which the reversible front member is frictionally and releasably held in the selected positions of reversal.

A further object of the invention is to provide a cuff link provided with a reversible front member having differing ornamental characteristics on the inner and outer surfaces thereof for exposure to view, interchangeably, and thereby providing in the one cuff link a front member capable of manipulation to provide, in use, a two-in-one ornamental cuff link.

It is still further designed to provide a reversible front member for a cuff link carrying differing ornamental characteristics on the inner and outer faces thereof for interchangeable positioning to view on the wearer.

With the above and other objects in view, the invention consists in the construction and novel combination and arrangement of parts herein-after fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

In the accompanying drawings:

Figure 1 is a perspective view of the invention;

Figure 2 is a perspective view of the invention showing the position of the front member reversed with relation to its position in Figure 1;

Figure 3 is a sectional view taken on the line 3—3 of Figure 2;

Figure 4 is a view partly in elevation, partly in section and partly broken away;

2

Figure 5 is a sectional view on the line 5—5 of Figure 3;

Figure 6 is a fragmentary sectional view illustrating the rear portion of a cuff link;

Figure 7 is a fragmentary view, lined to show the gold surface of the front member disposed outwardly; and

Figure 8 is a similar view showing the front member reversed to dispose the red color outwardly and the gold color inwardly.

Referring now more particularly to the accompanying drawing, the reference character 10 indicates, generally, the new cuff link including a suitable shank indicated, generally, by the reference character 11, and the reversible front member indicated, generally, at 12, and the rear member, in this instance, a pivoted bar 14, the essential feature of the invention being the reversible front member carrying differing coloring or other differing ornamental characteristics on its inner and outer surfaces for view or display interchangeably, thereby creating a two-in-one cuff link.

The shank 11 is illustrated as composed mainly of a short stem 15 and an aligning, substantially U-shaped element, both riveted rigidly together and the latter including spaced legs 16 and an inner connecting bight portion 17. The legs 16 preferably converge slightly to the rear of the cuff link and they are slightly resilient and at their free ends said rear member or bar 14 is pivoted on a suitable pivot 18 so that the bar 14 may swing inwardly between said legs in the plane of the axis of the shank or laterally of the shank at the rear end thereof and concealed from view behind the wearer's sleeve cuff. The arrow in Figure 4 indicates one direction of movement of the bar 14 on its pivot and obviously the said bar may be swung on its pivot in the opposite direction.

To hold the inner rear member or bar 14 in adjusted positions, a friction holding means is provided in the form of sets of protuberances 19 formed on the inner faces of each of the legs 16 adjacent said pivot 18 for coaction with similarly arranged sets of sockets 19' formed on opposite sides of the rear member or bar 14. The slight resiliency of the legs coacting with said sets of protuberances and said sets of sockets releasably maintain the rear member or bar 14 in adjusted positions.

The aforesaid short stem 15 has its inner end riveted at 20 or otherwise secured in an aperture 21 in the bight portion 17 of the said U-shaped portion of the shank, there being a small stop plate 22 fixed on said stem and resting on said

bight portion 17 to coat with the riveted inner end 20 of said stem to hold the stem and the U-shaped member in tight connection.

The stem 15 has a small, substantially oblong shaped plate 23 fixedly secured to the outer end thereof and which is secured fixedly by soldering or otherwise to the under surface of a rectangular or oblong-shaped head 24 to which latter the aforesaid reversible front member 12 is pivoted at 25 intermediate the ends of said head 24.

The head 24, in this particular instance, is formed of metal having rounded ends and on its outer surface has ornamental, alternately arranged ridges and grooves, as shown at 26 and 27, respectively, but it is to be understood that the head may be formed of material other than metal and that the outer surface of the same may be ornamented otherwise than as herein disclosed and as shown in the drawings.

The front member 12 is formed of metal or other material and is in the form of a shell 28 providing one face of the front member, the shell carrying a colored stone 29 on its other face providing a surface contrasting with the outer surface of the shell. The shell part of the front member may be of gold and the colored stone may be red in color. The colors are not important so long as there is a contrast in appearance. As shown, for purposes of illustration, the shell and stone parts are of the same substantially oval shape and they are soldered or otherwise connected or cemented together.

The shell 28 includes a flange or bead 30 to engage the edge of the colored stone 29 by way of further securing, if not providing the sole way of securing, said face parts 28 and 29 together as a unit.

It is to be understood, of course, that the instant invention comprehends a front member of any shape and which may be composed entirely of metal or entirely of stone, or other material, or of one piece, or of two differently colored or designed stones, in that one of the main purposes is to provide the front member on the inner and outer face portions thereof with contrasting colors or designs of different appearance for display or view, interchangeably. One surface may be gold color and the opposite surface red, or one surface possess characteristics different from the characteristics of the other surface.

The substantially oval shaped front member is pivoted at 25 to said head 24 intermediate the ends of the latter and it is provided at one end with a recess 31 similar in form to the rectangular shape of the head 24 and embraces the sides and the inner end of the head, the recess opening outwardly through the end of the front member so as to permit swinging movement of the front member back and forth on its pivot 25 intermediate the ends of said head and thereby present to view either surface of the front member, providing a front member of contrasting color or design on opposite surfaces thereof for display or wear, interchangeably, as may be desired by the wearer. When the front member is disposed at substantially a right angle to the shank as shown in Figs. 1 and 2 of the drawings, with either its outer or its inner face disposed outwardly, the head 24 substantially fills the recess in the front member, and the outer face of the head extends substantially flush with that face of the front member which is outwardly disposed and acts complementally thereto to present

a symmetrical design. The front member 25 is at all times in embracing relation with said head 24.

The reversal of the front member may be accomplished with the cuff button in operative position with relation to the wearer's cuff, as well as being shiftable to reverse positions before applying the cuff link to the wearer's cuff.

From another viewpoint, the pivotal mounting 16 of the front member on said head and the recess in the front member permits the latter to swing about said head in embracing relation therewith and laterally across the plane of the longitudinal axis of the shank to reverse the position 15 of the front member and consequently reverse and display said differing ornamental surfaces inwardly and outwardly, interchangeably. In either position, the front member is shown as offset with relation to the longitudinal axis of 20 the shank and the exposed ornamental surface is presented in full view on the outside of the wearer's sleeve cuff.

From the foregoing, it will be understood that the present invention comprehends a cuff link 25 provided with a front member possessing two-tone or contrasting colors or designs on opposite surfaces and shiftable alternately or interchangeably to present either of the contrasting tones, colors or designs to display or view and holding the front member in either of the reversed positions by virtue of a releasable friction holding means provided, in one instance, by the sets of small semi-spherical protuberances 32 projecting from the opposite sides of the recess 31, adjacent the ends thereof, and releasably riding into, entering, snapping, or springing into the corresponding sockets 33 in the ends of the sides of the head 24, on opposite sides of the pivot 25, when the front member is swung into reversed cooperative relation with the head 24.

Means other than just described exists in the drawings to hold the front member releasably on the head member, say for instance, one set of protuberances at one end of the recess in the front member to snap or spring or frictionally enter sets of sockets, interchangeably, at the ends of the head on opposite sides of said pivot 25. In other words, the front member 25 may be frictionally and releasably held on the head 24 in reversed positions by one or two sets of the protuberances on the sides of the recess to snap into or frictionally and releasably enter corresponding cooperating cavities or sockets in the side of the head 24 at the ends thereof, and on opposite sides of said pivot, as described.

The invention, in fact, comprehends any suitable releasable holding means between the head and the front member to releasably hold the front member in its reversed positions on the head 60 insofar as is permitted by and within the scope of the appended claims.

It is to be noted also that the instant invention comprehends a cuff link including a shank member and a shiftable front member with a friction device between the said members operable to hold the front member in position on the shank member, and also comprehending a structure of cuff link, including a shank, a head on the shank, and a front member having operative embracing relation with said head, independently of a separate holding means. If the front member becomes accidentally loose on the shank or a head member thereon, and swings outwardly, with or without a holding means, the front mem-

ber would not become lost, it being tied in with the link.

This application contains claims broadly covering reversible cuff link constructions disclosed in application, Serial No. 111,917, filed August 23, 1949, and application, Serial No. 112,979, filed August 29, 1949, the two latter cases disclosing modified forms of the reversible front member and means for releasably holding the same with either side face thereof disposed outwardly to view. The modified forms of the invention shown in the cases referred to are not disclosed in the present case.

The present new and novel cuff link provides a permanently two-in-one cuff link for use by a wearer, enabling him to expose outwardly either of two ornamental front member surfaces as may be desired without separating the front member from the cuff link, as stated herein, and if desired, without removing the cuff link from the wearer's shirt cuff.

What is claimed is:

1. A reversible cuff link, including a shank having means at one end thereof for releasably retaining the cuff link in a cuff link opening, a head member secured to the other end of the shank and having parallel sides, a reversible front member pivoted at a point a short distance from one end thereof on said head and having differing ornamental characteristics on its inner and outer faces and provided with a recess having parallel sides paralleling said parallel sides of said head member when the front member is positioned in either of its reversed positions on said head, and releasable, frictional, interengaging elements carried by the head and the front member to hold the latter in either of said positions on said head.

2. A cuff link including a shank, an elongated head on one end of the shank rigidly secured thereto, and a front member having inner and outer faces of differing ornamental character, said front member having an elongated recess extending inwardly from one end thereof corresponding substantially in size to said head to receive the latter therein, said front member at a point substantially centrally of the ends of said recess being pivotally connected to the head intermediate the ends of the head with the side walls of said recess straddling the head and providing for pivotal movement of the front member on the head to interchangeably position the front member disposed at substantially a right angle to the shank with either its inner or its outer side face disposed outwardly to view and extending substantially flush with the outer face of said head, and means for releasably holding the front member in either of said positions.

3. A cuff link including a shank having a head at one end thereof, and a front member having inner and outer faces upon which different ornamentation can be applied, said front member having an open-ended recess formed therein substantially complementary in shape and size to said head, said front member being pivotally carried by said head and movable to either of two positions substantially perpendicular to the axis of the shank with either of the inner and outer faces disposed outwardly to view, and means for releasably holding the front member in either of said positions.

4. A cuff link including a shank having an enlarged head rigidly secured to one end thereof, a front member having inner and outer faces upon which different ornamentation can be applied, said front member having a recess open

at one end formed therein substantially complementary in shape and size to said head, said front member being non-removably pivotally carried by said head and movable to either of two positions substantially perpendicular to the axis of the shank with either of the inner and outer faces disposed outwardly to view, and means for releasably holding the front member in either of said positions.

5. A cuff link including a shank having an enlarged head rigidly secured to one end thereof, a front member having inner and outer faces upon which different ornamentation can be applied, said front member having a recess open at one end formed therein substantially complementary in shape and size to said head, said front member being pivotally carried by said head and movable to either of two positions substantially perpendicular to the axis of the shank with either of the inner and outer faces disposed outwardly to view, said head having arcuate end surfaces to permit close cooperation with the pivotal front member, and means for releasably holding the front member in either of said positions.

6. A cuff link including a shank having an enlarged head rigidly secured to one end thereof, and a front member having inner and outer faces upon which faces different ornamentation is applied, said front member having an open-ended recess formed therein substantially complementary in shape and size to said head, said front member being pivotally carried by said head and movable to either of two positions substantially perpendicular to the axis of the shank with either of the inner and outer faces disposed outwardly to view and opposing wall portions of said recess in the front member and juxtaposed wall portions of the head being formed with projections and indentations for releasably holding said front member in either of said positions.

7. A cuff link including a shank having an enlarged head rigidly secured to one end thereof, and a front member having inner and outer faces upon which different ornamentation can be applied, said front member having an open-ended recess formed therein substantially complementary in shape and size to said head, said front member being pivotally carried by said head and movable to either of two positions substantially perpendicular to the axis of the shank with either of the inner and outer faces disposed outwardly to view and opposing walls of said recess in the front member and juxtaposed faces of the head being formed with projections and indentations for releasably holding said front member in either of said positions, said projections and indentations being located remotely from the pivotal axis of said front member.

8. A cuff link including a shank having a head immovably secured to one end thereof and being of such size as to be impassable through the cuff opening of a shirt either while being inserted or while in use, the longitudinal axis of said head lying in a plane perpendicular to the axis of said shank and the head constituting a part of the face portion of the cuff link, a front member having opposite faces upon which faces different ornamentation is applied, said front member having a slot therein open at an edge portion thereof, the slot being substantially complementary in shape and size to said head with an edge of said head substantially flush with the edge portions of said front member defining the opening therein, said front member being pivotally attached to and

carried by said head so that the said front member can be swung on the pivot to expose either face thereof and with the head thus substantially filling the slot in said front member and in either of the positions of the front member the opposite end portions of the head will be substantially flush with the edge portions of the front member defining the opening therein, and cooperative and concealed means releasably retaining said front member and said head in either of said relative positions.

9. A cuff link including a shank having a head immovably secured to one end thereof and being of such size as to be impossible through the cuff opening of a shirt either while being inserted or while in use, the longitudinal axis of said head lying in a plane perpendicular to the axis of said shank and constituting a part of the face portion of the cuff link, a front member having opposite faces upon which faces different ornamentation is applied, said front member having a slot therein open at an edge portion thereof, the slot being substantially complementary in shape and size to said head with an edge of said head substantially flush with the edge portions of

5

said front member defining the opening therein, said front member being pivotally attached to and carried by said head about an axis medially of said head so that the said front member can be swung on the pivot to expose either face thereof and with the head thus substantially filling the slot in said front member and in either of the positions of the front member the opposite end portions of the head will be substantially flush with the edge portions of the front member defining the opening therein, and an obscured wall portion of said slot in the front member and a juxtaposed obscured wall portion of the head being formed with projections and indentations for releasably holding said front member in either of said positions.
